UNITED STATES PATENT OFFICE

EDWIN S. MIX, OF ROCHESTER, NEW YORK, ASSIGNOR TO HICKOK MANUFACTURING COMPANY, INC., OF ROCHESTER, NEW YORK, A CORPORATION OF NEW YORK

BELT FOR PERSONAL WEAR

Application filed June 7, 1928. Serial No. 283,646.

The present invention relates to belts for personal wear such as garters and waist belts and an object thereof is to provide an improved construction which is adjustable to provide different sizes of belts while at the same time having a fixed adjusted position. Another object of the invention is to provide an improved construction which will have no metal parts exposed on the inner face of the belt for contact with the clothes of the user. A further object of the invention is to provide upon one end of the belt an adjustable slide having a fixed anchoring projection on the inner face of the belt, and upon the other end of the belt an anchoring device spaced from such end for cooperation with the anchoring device on the slide so that the said last mentioned end of the belt will act to cover the connection between both anchoring devices. Still other objects of the invention are to improve the construction of the slide as well as the anchoring device for interlocking therewith.

To these and other ends, the invention consists of certain parts and combinations of parts, all of which will be hereinafter described: the novel features being pointed out in the appended claim.

In the drawings:

Fig. 1 is a perspective view of a garter belt constructed in accordance with this invention;

Fig. 2 shows the front face of the belt in extended position, parts being broken away to illustrate the construction of the anchoring device on one end of the belt;

Fig. 3 is a view of the inner face of the belt in extended position;

Fig. 4 is an enlarged section showing the slide having its anchoring device connected to the anchoring device on the opposite end of the belt; and

Fig. 5 is a rear face view of the slide.

Referring to the illustrated embodiment of the invention, 1 indicates the strap which, in this instance, is formed of elastic material preferably an elastic core with a leather covering such as described in the patent to Scheuer, No. 1,192,691, granted July 25, 1916.

Adjustably mounted on this belt near one

end is a slide comprising, in this instance, three bars 2, 3 and 4, spaced apart to provide two slots 5, the bars and slots being parallel, and the bars being connected at their ends by cross pieces 6. In this instance, the bars and cross pieces are formed from one piece of sheet metal, the cross pieces 6 being deflected laterally or rearwardly so as to provide side flanges on the slide. Arranged on the central or intermediate bar 3 is a hook or anchoring device 7. This hook or anchoring device may also be formed in one piece with the slide and is a substantially U-shaped member having its ends extending from the central bar 3. In this instance, this hook or anchoring device is cut from the material so as to utilize the portion cut from one of the slots 5, portions of its arms being cut from the bar 3. These latter portions are bent laterally with reference to the bar 3 while the portion cut from the slot 5 is curved. The strap 1 is laced through the two slots 5 in front of the bar 3, so that the hook 7 lies on the rear face of the strap where it is invisible. It is apparent that, the slide may be slid along the strap to any desired position, the edges of the bars 2, 3 and 4 acting to prevent the slipping of the slide due to the fact that a bend is provided in the strap. The strap is as wide as the slots are long and the slots extend to the rearwardly deflected cross pieces 6 so that the latter act as guides for the strap which engages the cross pieces on the outer sides of the two slots.

On the opposite end of the strap is arranged an anchoring device. In this instance, this anchoring device is secured to the strap by an end piece comprising two layers of leather 8 and 9 stitched together at their edges at 10 with a portion of the strap 1 introduced between them. This strap portion 1 is skived or beveled so as to reduce its thickness and this beveled portion is received between the two pieces 9 and 8 adjacent one end of said pieces so that the stitches 10 also anchor the end pieces to the strap, the end pieces however, in effect, being a continuation of the strap. The anchoring device, in this instance, is a plate member formed with two slots 12 and 13 providing three bars 14, 15 and 16.

16 connected by cross pieces 17. The bar 16 is widened at 19 at its center and is received between the two pieces 8 and 9, the piece 8 being passed through the slot 13 in spaced relation to the end of the strap. Stitches 20 and 5 21 are also passed through the two pieces 8 and 9 on opposite sides of the bar 16 and serve to prevent the turning of the bar 16 on the strap. The cross bars 17 are deflected at 22 between the bars 14 and 15 so that the bar 14 10 lies to one side of the plane of the bars 15 and 16 and in spaced relation to the adjacent face of the piece 8 and also in spaced relation to the end of the strap. Through this construction, the bar 14 lies on the front face of 15 the strap and may be readily engaged with the hook 7 on the rear face of the other end of the strap, the strap end projecting beyond the point of interengagement between the 20 two parts and serving to prevent any metal contact with the user on the entire inner face of the strap when the parts are in interlocking relation. The elastic belt serves to hold the two anchoring devices together.

25 What I claim as my invention and desire to secure by Letters Patent is:

In a belt, the combination with a strap having an end piece formed of two pieces of sheet material stitched together at their edges and 30 having the body of the strap received between them and held by said stitches, and an anchoring device having two bars, one of which lies between the two pieces of the end member, and the other of which is deflected away from 35 the end member, and stitching passing through the two pieces on opposite sides of the first mentioned bar to secure the anchoring device to the strap end beyond such end.
